UNITED STATES PATENT OFFICE.

WILLIAM BEALL GRAY, OF LOUISVILLE, KENTUCKY, ASSIGNOR TO MARTIN J. BANNON,
OF LOUISVILLE, KENTUCKY.

INSULATING PIPE-CONDUIT.

1,159,930.

Specification of Letters Patent.

Patented Nov. 9, 1915.

Original application filed September 30, 1912, Serial No. 723,206. Divided and this application filed August 2, 1913. Serial No. 782,661.

To all whom it may concern:

Be it known that I, WILLIAM BEALL GRAY, a citizen of the United States, and a resident of Louisville, in the county of Jefferson and State of Kentucky, have invented 5 a new and useful Improvement in Insulating Pipe-Conduits, of which the following is a specification.

My invention is an improvement in insulating pipe conduits, and has for its object to provide a conduit of the character specified, having means within the conduit for carrying pipe supports of the character shown in my co-pending applications, 10 Serial No. 720,524, filed Sept. 16, 1912; Serial No. 709,262, filed July 13, 1912; Serial Nos. 765,281 and 765,282, filed May 3, 1913; and the present application is a divisional 15 application of my co-pending application, Serial No. 723,206, filed Sept. 30, 1912, for a patent on separable earthen insulating 20 pipe conduits.

In the drawings: Figure 1 is a perspective view of one end of a conduit, constructed 25 in accordance with the invention, Fig. 2 is a transverse vertical section of the same, Fig. 3 is a similar view of a modified form of conduit, and Figs. 4 and 5 are front views of a portion of one of the supporting ribs, 30 showing modified forms of notches.

In the present embodiment of the invention, the conduit is shown as circular in cross section, but it is obvious that the carrying means could be arranged in conduits 35 of other cross sectional shape with equal facility, and the sections of the conduits may be of any desired length and diameter, in accordance with the conditions to be met.

In the construction of Figs. 1 and 2, each 40 section 1 of the conduit is provided at one end with an outwardly offset annular flange 2, for receiving the adjacent end of the succeeding section or joint. In the body of the conduit, longitudinally extending ribs 45 or ledges 3 are provided, the said ribs or ledges being so arranged that one face of the ribs or ledges is in the same plane while the other face of each rib or ledge is parallel with the adjacent face of the other rib or ledge. At suitable intervals, the ribs or 50 ledges are provided with notches or recesses 4, the said notches being arranged in series of two, and each notch of one rib being in register with a notch of the other rib.

It will be noted from an inspection of Fig. 1, that each of the notches has its bottom rounded from side to side or arc-shaped, and the said notches or ribs are designed to receive the ends of the shaft or of the cross bars of the cradles shown in my 55 above-mentioned co-pending applications, Serial No. 720,524, filed Sept. 16, 1912; Serial No. 709,262, filed July 13, 1912; Serial Nos. 765,281 and 765,282, filed May 3, 1913; and the shaft or cradle extends across the 60 space between the ribs.

The conduit shown in Figs. 1 and 2 is designed to be separated into upper and lower sections to permit the pipe to be laid in the lower sections, and afterward to permit the 70 upper sections to be placed in position and cemented to the lower section. For this purpose, each section of the conduit is provided with two pairs of oppositely arranged 75 scores or cuts 5 and 6, each score or cut inclining inwardly and downwardly as shown. The said scores or cuts 5 and 6 are of considerable depth, and each decreases in width toward its bottom, and the said pairs are so arranged that when the material of the conduit between the cuts is broken, the conduit will be separated into approximately half 80 sections. The conduit is provided on its inner surface above each score 5 with a longitudinally extending rounded rib 7, for reinforcing the conduit and especially to reinforce the upper half of the conduit along the separating line to insure the pipe fracturing where intended. The conduit section is also provided with an external longitudinal rib 8 at each of the 85 scores or cuts 6, the said ribs 8 being arranged below the scores or cuts, so that when the conduit is separated into upper and lower sections, the ribs 8 will be with 90 the lower section. The upper face of the rib 8 is horizontal as shown, so that cement may be arranged on the said upper faces and within the scores or cuts 6, after the upper half has been placed, whereby to cement 95 the halves of the conduit sections together.

In the construction of Fig. 3, a circular conduit 9 is shown, and the conduit is provided with ribs 10 of the same shape as the ribs 3, and similarly located in the conduit, 105 and with respect to each other. The ribs are provided with the notches or recesses 11, corresponding in shape and location to the

notches 4 and for the same purpose. The ribs or ledges 3 in addition to their function as a support for the cradles which carry the pipe, serve an additional function as reinforcements for the conduit, and especially in that class of conduit shown in Figs. 1 and 2. When the said conduits are laid after being separated into upper and lower sections or portions, the lower portions carry the entire weight of the pipe and the supporting mechanism interposed between the pipe and the conduit. After the upper section or portion has been laid and cemented in place, the said upper portion assists in carrying the weight. In addition, any water that may seep or leak into the conduit may flow away to the junction box well or drain between the ribs, thus escaping without wetting the pipe cover. Thus the said water will not interfere with or hinder the function of the pipe.

In Figs. 4 and 5, modified forms of notches are shown, for receiving the extended ends of the cradle. In Fig. 4, the supporting rib or ledge 12 has notches 13, each of which is of lesser width at the upper face of the ribs than at approximately the center of the notch. That is, the side walls of the notch are undercut. The extended end 14 of the cradle which supports the pipe is received within the notch and it will be noted that the said end 14 is provided with a groove 19 in one of its sides, the said groove being adapted to receive a portion of the cement or lead filling 16, which is placed in the notch to prevent disengagement of the cradle. In the construction of Fig. 5, the rib 17 has notches 18, each of which has in one side wall a notch or recess 19. The extended end 20 of the cradle is also provided with a notch 21, and the cement or lead filling 22 enters the notches 19 and 21, to form a lock for preventing disengagement of the cradle. It will be obvious that many different varieties or arrangements of locking means might be made use of.

I claim:—

1. A conduit of the character specified, having a pair of longitudinally extending approximately parallel internal integral ribs, the upper faces of the said ribs being in approximately the same plane, each rib having spaced pairs of notches, the notches of the ribs registering and each notch being laterally extended at one side thereof to form a lock for a sealing material.

2. A conduit of the character specified,

having a pair of longitudinally extending approximately parallel internal integral ribs, the upper faces of the said ribs being in approximately the same plane, the said ribs having notches in their upper faces, and each notch having a lateral extension for receiving a sealing material for the purpose specified.

3. A conduit of the character specified having a pair of longitudinally extending approximately parallel internal integral ribs, the upper faces of the said ribs being in approximately the same plane, the said ribs having notches in their upper faces, each notch being adapted to receive a sealing material, and having means for preventing upward movement of the said sealing material.

4. A conduit of the character specified, having a pair of longitudinally extending internal ribs, the upper faces of the ribs being in approximately the same plane, and each of the said upper faces having notches arranged in spaced relation, the notches of one rib registering with the notches of the other rib, and one of the side walls of each notch being recessed.

5. A conduit of the character specified, having a pair of longitudinally extending internal ribs, the upper faces of the ribs being in approximately the same plane, and each of the said upper faces having notches arranged in spaced relation, the notches of one rib registering with the notches of the other rib, the said notches being adapted for engagement by the supporting fingers of a pipe supporting cradle, and the notches being of greater cross section than the cross section of the fingers for permitting the insertion of a sealing medium, and means in connection with the notches and the fingers for receiving a portion of the sealing medium to form a lock.

6. A conduit of the character specified, having a pair of longitudinally extending internal ribs, the upper faces of the ribs being in approximately the same plane, and each of the said upper faces having notches arranged in spaced relation, the notches of one rib registering with the notches of the other rib, one of the side walls of each notch being undercut for the purpose specified.

WILLIAM BEALL GRAY.
